UNITED STATES PATENT OFFICE.

WILLIAM E. MILLER, OF GOBLEVILLE, MICHIGAN.

WRAPPING-MACHINE.

1,324,463.

Specification of Letters Patent.

Patented Dec. 9, 1919.

Application filed March 11, 1919. Serial No. 281,927.

To all whom it may concern:

Be it known that I, WILLIAM E. MILLER, a citizen of the United States, residing at Gobleville, county of Van Buren, State 5 of Michigan, have invented certain new and useful Improvements in Wrapping-Machines, of which the following is a specification.

This invention relates to improvements in 10 wrapping machines.

My improved wrapping machine is especially designed by me for the wrapping of wax paper upon loaves of bread and the like, although desirable for use in other relations.

The main objects of this invention are:

First, to provide an improved wrapping machine which is simple and convenient to use.

Second, to provide an improved wrapping machine which is simple and economical and compact in structure.

Further objects, and objects relating to structural details, will definitely appear 25 from the detailed description to follow.

I accomplish the objects of my invention by the devices and means described in the following specification. The invention is clearly defined and pointed out in the claims.

30 A structure which is a preferred embodiment of my invention is clearly illustrated in the accompanying drawing, forming a part of this specification, in which:

Figure I is a plan view of a structure 35 embodying the features of my invention, the same being shown in operative relation to a sealing machine.

Fig. II is a detail side elevation, a loaf of 40 bread with a wrapper about the same being shown in the machine.

Fig. III is a similar detail side elevation with the flaps partially folded, the rear flap 45 folders being shown in actuated position.

Fig. IV is a detail side elevation showing 50 a loaf in its last folding position.

Fig. V is an enlarged detail longitudinal section on a line corresponding to line 5-5 of Fig. I showing details of the rear flap folder mechanism.

55 Fig. VI is an enlarged detail longitudinal section on a line corresponding to line 6-6 of Fig. I, showing further details of the flap folder mechanism.

Fig. VII is a top view of one of the front 60 flap folders shown in one position by full

lines and in another position by dotted lines.

Fig. VIII is an enlarged detail vertical section on a line corresponding to line 8-8 of Figs. I and III, showing details of the 60 top and bottom flap folders.

In the drawing similar reference characters refer to similar parts throughout the several views and the sectional lines are taken looking in the direction of the little 65 arrows at the ends of the section lines.

Referring to the drawing, 1 represents a sealing machine. As the details of this machine form no part of my present invention 70 they are not illustrated or described herein.

75 My improved wrapping machine comprises a pair of bed members 2 and 3, the bed member 3 being secured upon the standards 4 by means of the bolts 5. The bed member 2 rests upon the standards 4 and is slidably mounted upon the rods 6 projecting from the bed member 3.

A screw 7 is provided for adjusting the bed member 2 relative to the bed member 3 thereby adapting the machine for loaves or 80 other articles of different size. On these bed members 2 and 3 are way bars 8 forming a way upon which the loaf to be wrapped is pushed through the machine. The forwardly inclined plate 9 constitutes 85 the front of the way. This plate is secured to one way bar as at 10, the other side overlapping but being unconnected with the other way bar, so that it does not interfere with the adjusting of the machine. 11 indicates the loaf to be wrapped and 12 its 90 wrapper.

For convenience in description I refer to the flaps as rear, front, bottom and top flaps, 95 13 indicating the rear flap, 14 the front flap, 15 the bottom flap and 16 the top flap,—see Fig. IV.

The article to be wrapped is pushed along the way by hand, the wrapper having been first partially wrapped around the article, 100 the ends or flap fold portions being unfolded. As the article is pushed along the way it engages the trip 17 of the catch 18 which coacts with the keeper 19 on the rock shaft 20 to retain the rock shaft in its initial position. This rock shaft is disposed transversely below the way and carries the flap folders 21 which swing forwardly when the trip is released to fold the rear flaps 13 forwardly upon the article, the rock shaft 110

being actuated when released by the coiled spring 22, one end of which is secured to the bed and the other to an arm 23 on the rock shaft. On the rock shaft is a return lever 23'.

A spring 24 urges the catch into engaging position and yieldingly supports the trip in position to be engaged by the article. The front flaps are folded rearwardly upon the 10 folded rear flaps by means of the blade-like front flap folders 25 which are mounted on posts 26 disposed at each side of the way so that the flap folders project inwardly and forwardly as shown in Fig. I. Springs 27 15 urge these flap folders 25 inwardly. As the article is pushed along its bottom flap 15 is engaged by the rearwardly inclined flap folders 28 which are disposed to project upwardly at the sides of the way. The 20 upper edges of these flap folders are preferably turned outwardly at 29. The top flaps 16 are turned downwardly upon the bottom flap by means of the top flap folders 30 which are forwardly inclined and 25 disposed at the sides of the way to overhang the bottom flap folders 28, the top and bottom flap folders being so arranged that the bottom flaps are turned or folded prior to the completion of the folding of the top 30 flaps.

After leaving the flap folders the flaps are retained in their folded relation or held against the ends of the article by the plates 31 until they are engaged by the side plates 35 32 of the sealing machine.

My improved sealing machine is very simple and economical in structure and at the same time enables the rapid and satisfactory wrapping of articles such as loaves of bread.

40 I have illustrated and described my improvements as I have embodied and adapted the same for wrapping loaves of bread. I have not attempted to illustrate or describe other modifications or adaptations as 45 I believe the disclosure made will enable those skilled in the art to which my invention relates to embody or adapt the same as may be desired.

Having thus described my invention, what 50 I claim as new and desire to secure by Letters Patent, is:

1. In a wrapping machine, the combination of a way, a rock shaft disposed transversely below the way, an actuating spring 55 for said rock shaft, a catch for retaining said rock shaft in its initial position provided with a trip projecting into the path of an article pushed along the way, a pair of rear flap folders on said rock shaft which 60 swings forwardly when said trip is released and folds the rear flaps forwardly, a return lever for said rock shaft, posts disposed at the sides of the way, yielding forwardly and inwardly projecting front flap 65 folders mounted on said posts and provided

with springs urging them inwardly so that the front flaps are folded rearwardly as the article is pushed along the way, a pair of rearwardly inclined bottom flap folders disposed at the sides of the way engaging the 70 bottom flaps and folding them upwardly as the article is pushed along the way, and a pair of forwardly inclined top flap folders disposed at the sides of the way overhanging said bottom flap folders engaging the 75 top flaps and folding them downwardly as the article is pushed along the way.

2. In a wrapping machine, the combination of a way, a rock shaft disposed transversely below the way, an actuating spring 80 for said rock shaft, a catch for retaining said rock shaft in its initial position provided with a trip projecting into the path of an article pushed along the way, a pair of rear flap folders on said rock shaft which 85 swings forwardly when said trip is released and folds the rear flaps forwardly, a return lever for said rock shaft, yielding front flap folders mounted so that the front flaps are folded rearwardly as the article is pushed 90 along the way, a pair of rearwardly inclined bottom flap folders disposed at the sides of the way engaging the bottom flaps and folding them upwardly as the article is pushed along the way, and a pair of forwardly 95 inclined top flap folders disposed at the sides of the way overhanging said bottom flap folders engaging the top flaps and folding them downwardly as the article is pushed along the way.

3. In a wrapping machine, the combination of a way, a rock shaft disposed transversely below the way, an actuating spring for said rock shaft, a catch for retaining said rock shaft in its initial position provided with a trip projecting into the path of an article pushed along the way, a pair of rear flap folders on said rock shaft which 105 swings forwardly when said trip is released and folds the rear flaps forwardly, yielding front flap folders disposed so that the front flaps are folded rearwardly upon the rear flaps as the article is pushed along the way, a pair of rearwardly inclined bottom flap folders disposed at the sides of the way 110 engaging the bottom flaps and folding them upwardly as the article is pushed along the way, and a pair of forwardly inclined top flap folders disposed at the sides of the way overhanging said bottom flap folders 115 engaging the top flaps and folding them downwardly upon the bottom flaps as the article is pushed along the way.

4. In a wrapping machine, the combination of a way, a rock shaft disposed transversely below the way, an actuating spring for said rock shaft, a catch for retaining said rock shaft in its initial position provided with a trip projecting into the path 120 of an article pushed along the way, a pair of 125 top flap folders disposed at the sides of the way overhanging said bottom flap folders engaging the top flaps and folding them downwardly upon the bottom flaps as the article is pushed along the way.

- rear flap folders on said rock shaft which swings forwardly when said trip is released and folds the rear flaps forwardly, a return lever for said rock shaft, posts disposed at 5 the sides of the way, yielding forwardly and inwardly projecting front flap folders mounted on said posts and provided with springs urging them inwardly so that the front flaps are folded rearwardly as the 10 article is pushed along the way, and top and bottom flap folders disposed at the sides of said way to fold the flaps as the article is pushed along the way.
5. In a wrapping machine, the combination of a way, a rock shaft disposed transversely below the way, an actuating spring for said rock shaft, a catch for retaining said rock shaft in its initial position provided with a trip projecting into the path 20 of an article pushed along the way, a pair of rear flap folders on said rock shaft which swings forwardly when said trip is released and folds the rear flaps forwardly, front flap folders mounted so that the front flaps are 25 folded rearwardly as the article is pushed along the way, and top and bottom flap
- folders disposed at the sides of said way to fold the flaps as the article is pushed along the way.
6. In a wrapping machine, the combination of a pair of base members, a pair of bed members one of which is secured to said base members and the other of which is adjustably supported thereon, guide rods carried by said bed member secured on said 30 base members and slidably associated with the other bed member, an adjusting screw for said adjustable bed member, a pair of way bars mounted on said bed members, a rock shaft disposed below said bed members, 35 means for actuating said rock shaft comprising a trip disposed to be engaged by an article pushed along on said ways, a pair of rear flap folders on said rock shaft one of which is adjustable thereon, and front, top 40 and bottom flap folders mounted on said bed members.
- 45

In witness whereof I have hereunto set my hand and seal in the presence of a witness.

WILLIAM E. MILLER. [L.S.]
